UNITED STATES PATENT OFFICE

WILLIAM M. BLECKER, OF CANTON, OHIO, ASSIGNOR OF FIFTY-ONE PER CENT TO
EDWARD A. LANGENBACH, OF CANTON, OHIO

CONTINUOUS STRIP MILL

Application filed June 23, 1928. Serial No. 287,746.

The invention relates to the continuous rolling of strips or sheet strips, and is an improvement upon and continuation of the common subject matter of my copending application Serial No. 213,317, filed August 16, 1927.

The object of the improvement is to provide a continuous rolling apparatus in which slabs from a blooming mill or slab mill may be continuously rolled into cold rolled or hot rolled and annealed strips, means being provided for cooling the hot strip down to pickling temperature and continuously pickling the same as it passes from the hot rolls; for washing and drying the pickled sheets and again cooling the sheets as they pass from the drier before entering the cold rolls, continuously annealing means being provided beyond the cold rolls, an additional stand or stands of cold rolls being located beyond the annealing furnace for giving the strips the desired hardness after annealing, means being provided beyond the last named cold rolls for either shearing the strips into sheet lengths or coiling the same; means being also provided for passing the strips around the pickling and cold rolling mechanism, from the hot rolls to the annealing furnace, for the production of hot rolled annealed strips.

An embodiment of the invention thus set forth in general terms is illustrated in the accompanying drawings, in which—

Figures 1, 1a and 1b are a complete plan sectional view of the improved apparatus; and

Figs. 2, 2a and 2b are a complete vertical sectional view through the apparatus, showing the mechanism for rolling cold rolled strips from the slabs.

Similar numerals refer to similar parts throughout the drawings.

The blooming mill or slab mill is shown generally at 1, being provided with a roller conveyer 2 for carrying the slabs or the like to and from the mill. The slabs may be sheared to the desired size by a shear indicated generally at 3 located beyond the slab mill, and in position to receive slabs from the conveyer 2.

If desired, the slabs, after being sheared,

may be turned as by the slab turning table shown at 4, which may be rotated by any suitable and well known means, in order to turn the slab for cross rolling before the same is passed to the conveyer 5 extending through 55 and beyond the heating furnace 6.

A plurality of stands of hot mills, illustrated generally at 7, 8, 9, 10 and 11, is located in succession beyond the heating furnace, each stand being positioned further from the preceding stand than the next preceding stand of rolls in order to compensate for the continuous elongation of the hot strip as it passes through the several stands of hot mills.

A series of conveyers 12 may be located between adjacent stands of hot mills for carrying the strip from one mill to the next, and, if desired, edge rolls 13 may be located between adjacent hot mills for the purpose of rolling the edges of the hot strip as it passes 70 through the mills.

A conveyer 14 is located beyond the last stand of hot rolls for carrying the hot strip to a cooler 15, provided for cooling the strip down to pickling temperature. Inlet and 75 outlet pipes 16 and 17 respectively, may be provided in the cooler for continuously circulating cold air or inert gas through the cooler and over the hot strips, in order to quickly cool the same to the desired temperature.

A shear 18 may be provided between the transfer table 14 and the cooler 15, as shown, or, if desired, at any point between the hot mills and the cold rolls to be hereinafter described, for the purpose of shearing the ragged front edge of the strip before the same enters the cold rolls.

A pair of feed rolls 19 may be located beyond the cooler for passing the cooled strip 90 through the pickling tank 20, which may be formed of acid resisting steel or the like.

Guides 21 may be provided in the tank for passing the strip down through the pickling solution, and a substantially air-tight cover 95 22 may be provided upon the pickling tank, a suction pipe 23 leading therefrom to a fan or the like, for the purpose of carrying away the fumes from the pickling bath and discharging them at any point outside of the 100

building or room in which the apparatus is located.

5 Pinch rolls 24 may be located beyond the pickling tank for passing the pickled strip on to the conveyer 25, which passes the strip to the washing tank 26, drying furnace 27 and cooler 28. This cooler may be of the same construction as the cooler 15 above described.

10 An edge trimmer 29 may be located between the cooler 28 and the plurality of stands of cold rolls 30, and, if desired, jets 31 may be located to impinge air, steam or other fluids diagonally across the surface of the strip before it enters the cold rolls, for the purpose 15 of removing scale and dirt from the surface of the strip.

15 The conveyer 25 may be arranged to carry the strip through the several stands of cold rolls, and then through a continuous non-oxidizing annealing furnace 32, in which the strip may be annealed and cooled down below scaling temperature as it passes through the furnace.

20 Beyond the annealing furnace steam jets 33 may be provided for further cleaning of the annealed strip. If desired, a roller leveler 34 may be provided for leveling or straightening the annealed strips which may first be passed through one or more stands 35 of cold 25 rolls to a shear 36 or coiler 37, in which the strips may be either sheared to sheet lengths or coiled, as desired.

25 Where it is desired to produce hot rolled annealed strips, the strips coming from the hot rolls may be transferred from the conveyer 14, by means of a transfer table 38 to a conveyer 39 and by-passed around the cooler 15, pickling tank, washing tank, drying furnace, cooler 28 and cold rolls 30, and then by means of a transfer table 40, may be 30 passed back on to the conveyer 25 and then may be passed through the annealing furnace roller leveler to the cold rolls 35 and so forth, as above described.

35 A shear 41 may be provided upon the conveyer 39 for trimming the front edge of the hot strip or for cutting the strips into desired lengths.

40 If it is desired to coil the hot rolled strips, a coiler 42 may be provided at one end of the conveyer 39, as shown in Fig. 1a, and the strips after being passed from the transfer table to the conveyer 39, may be moved backward to the coiler.

45 From the above, it will be obvious that slabs from the blooming mill or slab mill may be continuously passed through the apparatus to produce either cold rolled or hot rolled annealed strips, as desired.

50 I claim:—

1. An apparatus for continuous rolling of strips, including a slab mill, a plurality of stands of continuous strip rolling mills, a pickling tank, a drying furnace, a cooler, a plurality of stands of cold rolls, an annealing furnace, a shear, a plurality of stands of cold rolls, an anneal-

ing furnace, and means for passing material continuously through said apparatus.

2. An apparatus for continuous rolling of strips, including a plurality of stands of continuous strip rolling mills, a pickling tank, a drying furnace, a cooler, a plurality of stands of cold rolls, an annealing furnace, a shear, and means for passing material continuously through said apparatus. 70

3. An apparatus for continuous rolling of strips, including a slab mill, a plurality of stands of continuous strip rolling mills, a pickling tank, a drying furnace, a cooler, a plurality of stands of cold rolls, an annealing furnace, a coiler, and means for passing material continuously through said apparatus. 75

4. An apparatus for continuous rolling of strips, including a plurality of stands of continuous strip rolling mills, a pickling tank, a drying furnace, a cooler, a plurality of stands of cold rolls, an annealing furnace, a second stand of cold rolls, and means for passing material continuously through said apparatus. 80

5. An apparatus for continuous rolling of strips, including a slab mill, a plurality of stands of continuous strip rolling mills, a cooler, a pickling tank, a drying furnace, a second cooler, a plurality of stands of cold rolls, an annealing furnace, and means for passing material continuously through said apparatus. 85

6. An apparatus for continuous rolling of strips, including a plurality of stands of continuous strip rolling mills, a cooler, a pickling tank, a drying furnace, a second cooler, a plurality of stands of cold rolls, an annealing furnace, a shear, and means for passing material continuously through said apparatus. 90

7. An apparatus for continuous rolling of strips, including a plurality of stands of continuous strip rolling mills, a cooler, a pickling tank, a drying furnace, a second cooler, a plurality of stands of cold rolls, an annealing furnace, a coiler, and means for passing material continuously through said apparatus. 95

8. An apparatus for continuous rolling of strips, including a plurality of stands of continuous strip rolling mills, a cooler, a pickling tank, a drying furnace, a second cooler, a plurality of stands of cold rolls, an annealing furnace, a second stand of cold rolls, and means for passing material continuously through said apparatus. 100

9. An apparatus for continuous rolling of strips, including a slab mill, a plurality of stands of continuous strip rolling mills, a pickling tank, a plurality of stands of cold rolls, an annealing furnace provided with means for cooling the strips below scaling temperature, and means for passing material continuously through said apparatus. 105

10. An apparatus for continuous rolling of strips, including a slab mill, a plurality of stands of continuous strip rolling mills, a pickling tank, a plurality of stands of cold rolls, an annealing furnace provided with means for cooling the strips below scaling temperature, a shear, and means for passing material continuously through said apparatus. 5
11. An apparatus for continuous rolling of strips, including a slab mill, a plurality of stands of continuous strip rolling mills, a pickling tank, a plurality of stands of cold rolls, an annealing furnace provided with means for cooling the strips below scaling temperature, a coiler, and means for passing material continuously through said apparatus. 10
12. An apparatus for continuous rolling of strips, including a slab mill, a plurality of stands of continuous strip rolling mills, a pickling tank, a plurality of stands of cold rolls, an annealing furnace provided with means for cooling the strips below scaling temperature, a second stand of cold rolls, and means for passing material continuously through said apparatus. 15
13. An apparatus for continuous rolling of strips, including a heating furnace, a plurality of stands of continuous strip rolling mills, a pickling tank, a drying furnace, a cooler, a plurality of stands of cold rolls, an annealing furnace, and means for passing material continuously through said apparatus. 20
14. An apparatus for continuous rolling of strips, including a heating furnace, a plurality of stands of continuous strip rolling mills, a cooler, a pickling tank, a drying furnace, a second cooler, a plurality of stands of cold rolls, an annealing furnace, and means for passing material continuously through said apparatus. 25
15. An apparatus for continuous and simultaneous, selective rolling of hot rolled and annealed and cold rolled strips, including a heating furnace, a plurality of stands of continuous strip rolling mills, a pickling tank, a drying furnace, a plurality of stands of cold rolls, an annealing furnace, means for passing material continuously through said apparatus, and means for selectively bypassing material from the strip rolling mills to the annealing furnace. 30
16. An apparatus for continuous and simultaneous, selective rolling of hot rolled and annealed and cold rolled strips, including a plurality of stands of continuous strip rolling mills, a pickling tank, a drying furnace, a plurality of stands of cold rolls, an annealing furnace, means for passing material continuously through said apparatus, a transfer table between the strip rolling mills and the pickling tank, a conveyer communicating with the transfer table, and a trans- 35
- fer table communicating with the opposite end of the conveyer between the cold rolls and the annealing furnace. 70
17. An apparatus for continuous and simultaneous, selective rolling of hot rolled and annealed and cold rolled strips, including a slab mill, a plurality of stands of continuous strip rolling mills, a pickling tank, a drying furnace, a plurality of stands of cold rolls, an annealing furnace, means for passing material continuously through said apparatus, a transfer table between the strip rolling mills and the pickling tank, a conveyer communicating with the transfer table, a transfer table communicating with the opposite end of the conveyer between the cold rolls and the annealing furnace, and a coiler adjacent to one end of the conveyer. 75
18. An apparatus for continuous and simultaneous, selective rolling of hot rolled and annealed and cold rolled strips, including a slab mill, a plurality of stands of continuous strip rolling mills, a pickling tank, a drying furnace, a plurality of stands of cold rolls, an annealing furnace, means for passing material continuously through said apparatus, a transfer table between the strip rolling mills and the pickling tank, a conveyer communicating with the transfer table, a transfer table communicating with the opposite end of the conveyer between the cold rolls and the annealing furnace, and a shear associated with the conveyer. 80
19. An apparatus for continuous rolling of strips, including a turning table, a plurality of stands of continuous strip rolling mills, a pickling tank, a drying furnace, a cooler, cold rolls, an annealing furnace, and means for passing material continuously through said apparatus. 85
20. An apparatus for continuous rolling of strips, including a plurality of stands of continuous strip rolling mills, a pickling tank, a drying furnace, a cooler, a plurality of stands of cold rolls, an annealing furnace, and means for passing material continuously through said apparatus. 90
